US00D564749S

(12) **United States Design Patent** (10) **Patent No.:** **US D564,749 S**
Seamans (45) **Date of Patent:** **** Mar. 25, 2008**

(54) **FOOTWEAR**

(75) Inventor: **Scott Seamans**, Boulder, CO (US)

(73) Assignee: **Crocs, Inc.**, Niwot, CO (US)

(**) Term: **14 Years**

(21) Appl. No.: **29/245,453**

(22) Filed: **Dec. 19, 2005**

(51) **LOC (8) Cl.** **02-99**

(52) **U.S. Cl.** **D2/972**

(58) **Field of Classification Search** D2/902,
D2/904, 906-908, 943, 944, 947, 969, 972-974,
D2/909, 903, 953, 954, 925-942; 36/45,
36/50.1, 77 M, 77 R, 83, 88, 113, 114, 126-131,
36/84, 87, 102, 4

See application file for complete search history.

(57) **CLAIM**

The ornamental design for footwear, as shown and described.

DESCRIPTION

FIG. 1 is a front perspective view.

FIG. 2 is a front view.

FIG. 3 is a back view.

FIG. 4 is an outer side view.

FIG. 5 is an inner side view.

FIG. 6 is a top view.

FIG. 7 is a bottom view.

FIG. 8 is a front perspective view.

FIG. 9 is a front view.

FIG. 10 is a back view.

FIG. 11 is an outer side view.

FIG. 12 is an inner side view.

FIG. 13 is a top view; and,

FIG. 14 is a bottom view.

The broken line showing of the sole, upper, loop, cord, clasp, and stitching is for illustrative purpose only and forms no part of the claimed design. The cross-hatching and squiggle patterns of the upper are intended to represent fabrics and to cover the entire surface represented.
